(57) **CLAIM**

We claim the ornamental design for a robot cleaner, as
shown and described.

DESCRIPTION

FIG. 1 is a perspective view of a robot cleaner showing our
new design.

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines illustrating portions of the robot cleaner are
for environmental purposes only and form no part of the
claimed design.
